UNITED STATES PATENT OFFICE.

ARTHUR JOHN WILLIAM MUNDEN AND JOHN MITCHELL MUIR, OF DUNEDIN, NEW ZEALAND.

AUTOMATIC ELECTRICAL ANNOUNCER.

1,112,310.

Specification of Letters Patent. Patented Sept. 29, 1914.

Application filed June 19, 1912. Serial No. 704,662.

To all whom it may concern:

Be it known that we, ARTHUR JOHN WILLIAM MUNDEN, mechanic, and JOHN MITCHELL MUIR, hairdresser, subjects of His Majesty the King of Great Britain, residing at Imperial Buildings, 3 Dowling street, Dunedin, in the British Dominion of New Zealand, have invented certain new and useful Improvements in Automatic Electrical Announcers, and do hereby declare that the following is a full, clear, and exact description of the invention, such as will enable others skilled in the art to which it appertains to make and use the same.

This invention has reference to route indicating apparatus, and it comprehends, briefly, certain hereinafter described improvements in or relating to the mechanisms for effecting the requisite movements of the indicator proper, for stopping and reversing such movements, and for announcing each alteration in the said indicator consequent upon its movements.

An embodiment of the invention is indicated in the accompanying drawing, whereof:—

Figure 1 is a front elevation of the apparatus, with the cover of the casing, wherein it is disposed, removed; Fig. 2 is a transverse section taken on line A—B, Fig. 1; Fig. 3 is a plan view of Fig. 1; Fig. 4 and 4^a are respectively, a plan view of one of the winding rollers, and a detail sectional view of one of the bearings for said roller; Fig. 5 is a transverse section taken on line C—D, Fig. 1; Fig. 6 is a diagrammatic view of the wiring of the apparatus; Fig. 7 is a diagrammatic view of the wiring of the annunciator; Figs. 8 and 9 are side elevations showing two positions assumed by the armature included in the electromagnetic reversing mechanism; Fig. 10 is a perspective view of the apparatus; Fig. 11 is a fragmental front elevation of a modified form of the invention; Fig. 12 is a transverse section taken on line E—F, Fig. 11; Fig. 13 is a plan view of the armature shown in Figs. 11 and 12; and Fig. 14 is a diagrammatic view of the wiring for the aforesaid modification.

For the purpose of indicating the stopping places, there is employed a band 1, as in other inventions of the same class, and this band may be made of any thin, flexible material, and may have holes 2 punched

therein, adjacent to one edge and at equal distances apart, to receive the studs 3 affixed to the central roller 4, whereby motion is imparted by the band to the roller, regularity in the travel of the band is insured, and puckering of the band is prevented. Said band is mounted upon winding rollers 5 and 6. Each of the rollers 5 and 6 may be provided at one end, for convenience of mounting, with a movable spring bearing, such bearing consisting, in the construction illustrated, of a cap 8, and a plunger 7 whose stem works in said cap and is encircled by a spring 9 that bears against a flange 10 on said stem. The end of each plunger is thus held in engagement with the end of the corresponding roller 5 or 6, to assist in supporting the same and in preventing spinning when the current is cut off. The said rollers 5 and 6 are preferably demountable, so as to facilitate the changing of the band to suit different routes, and to accomplish this, they are provided at the opposite ends from those engaged by the plungers 7 with tongues 5^c and 6^c designed to fit in slots 80 formed in the corresponding bearings 5^d and 6^d; these tongues are provided, in turn, with small lugs 5^e and 6^e which project therefrom into said bearings, to center the rollers with respect to the driving gear. When the plungers 7 are forced inwardly of their caps, against the tension of springs 9, the opposite ends of the rollers 5 and 6 are released, whereupon the band may be lifted clear of the apparatus.

The apparatus necessary to effect the movement of the band comprises, briefly, a battery 11 to supply the electric current, conducting wires 12, a circuit closer or closers 13, and a motor 14 to actuate the roller mechanism. The automatic stop apparatus, Fig. 2, consists of a pair of electromagnets 15, a platinum-pointed contact screw 16, a pivoted armature 18, and a wire 17, the said wire being connected to the magnets and forming a circuit with the motor through the said screw to said armature by means of a spring 19 attached to the armature. In the construction shown, the armature is in the form of a lever pivotally mounted at one end and provided at its other end with an insulated detent 20, which latter is designed to engage in a pair of seats 23 formed in the central roller 4.

The circuit closers 13 may be simple push-buttons, and when one of them is actuated, the magnets 15 attract armature 18, thus releasing detent 20 from engagement 5 in seat 23 in roller 4 and making a contact with screw 16, which simultaneously completes the motor circuit. The closing of the latter circuit actuates the roller 5 or 6, and transmits motion to band 1 and to 10 roller 4. On releasing the push-button, the current is cut off from the electro-magnets 15, and the armature 18 is pulled back, under the influence of an adjustable tension spring 22, into position to engage its 15 detent 20 in the other seat 23 in roller 4, which latter continues to revolve until that seat is opposite said detent. Further movement is prevented by the disengagement of 20 spring 19 from screw 16, which breaks the motor circuit until the button is again pressed. The resistance of the magnets 15 must be slightly greater than that of the reversing magnets 24, Fig. 5, which latter attract the pivoted armature 46, so that 25 when once the connection is made by armature 18, the greater part of the current is shunted through the reversing magnets, thereby immediately energizing them, sufficient magnetism being retained in the magnets 15 to hold armature 18 in position until 30 released.

In the modified construction shown in Figs. 11 and 12, the indicating band 1 travels over a pair of guide rollers 5^A and 6^A 35 and is connected at its ends to a pair of winding rollers 5^B and 6^B, the rollers 5^A and 5^B being located at the top of the case wherein the apparatus is disposed, and the rollers 6^A and 6^B at the bottom of such 40 case. During its passage between the two guide rollers, the band crosses a small metal plate 25 having an aperture 26 therein, with which aperture a series of equally spaced 45 apertures 2' in said band successively register. In this form of the invention, the armature lever 18^A, which coacts with the magnets 15, has one end 27 extended laterally and provided with a roller 28, the other end 29 of said armature being connected 50 to a tension spring 22, so that when the magnets are deenergized, the said spring will force roller 28 through one of the apertures 2' into the aperture 26. This movement of said roller is sufficient to release 55 spring 19 from contact with screw 16 and thus break the motor circuit, whereupon the band is instantly stopped and is retained in position by the engagement of the roller in said apertures 2' and 26. To draw the 60 passengers' attention to an alteration in the indicator, an electric bell or similar annunciator 30 may be utilized. Said bell is connected by the wires 31, (Fig. 7), with battery 11, its circuit being normally open, and 65 being closed simultaneously with each al-

teration in the indicator by means of a suitable circuit closer 33, here shown as constituted by a spring whose free end projects into the path of a cam 32 on the adjacent end of roller 4. When said spring is 70 engaged by said cam, it will be pressed against a contact 33^A, thus completing the circuit. In the modified construction, the circuit closer is constituted by a contact finger 33^B which is connected to the end 29 75 of the armature lever 18^A, (Figs. 12 and 14), and is moved, consequent upon the attraction of said armature, into contact with a finger 33^C included in the bell circuit. Means is provided for reversing the direction of 80 travel of the band, such means being common to both forms and consisting, by preference, of a gear train, (Fig. 5), comprising a pair of gears 43 and 44 secured, respectively, to the winding rollers 5 and 6, (or 85 5^A and 5^B), a gear 45 fast on a spindle 47 carried by the armature 46 of the reversing magnets 24, and a second gear 48 also fast on said spindle and meshing with a driving gear 49, (Fig. 1), on the motor shaft 50. 90 Armature 46 is normally held in neutral position through the agency of springs 46^A which engage an extension 46^B on said armature. The gear 45 is designed to mesh alternately with the gears 43 and 44, consequent upon the rocking of armature 46, as will be understood, while the gear 48 is constantly in mesh with the driving gear 49. To control the reversing gearing, a suitable switch 51, attached to the case, may 100 be employed. The bell, or other annunciator 30, may also be mounted upon said case, as represented in Fig. 10.

The operation of the apparatus is believed to be apparent from the foregoing, 105 and, hence, to require no separate explanation.

We claim:—

1. In an indicating apparatus, the combination, with a traveling band, and winding rollers to which the band ends are connected, each of said rollers being provided with a gear; of a main circuit; a circuit closer therefor; an electro-magnet included in said circuit; an armature associated with said magnet; a shunt circuit; a motor, a contact and a pair of reversing magnets included in the shunt circuit; a gear shiftable alternately in opposite directions by the reversing magnets, to bring it into mesh alternately with the gears on said rollers; gear connections between the motor shaft and the shiftable gear for driving the latter; a contact finger carried by said armature for engagement with said contact when the first-named magnet is energized, to close said shunt circuit; and a reversing switch for controlling said reversing magnets. 115

2. In an indicating apparatus, the combination, with a traveling band, and winding 120

rollers to which the band ends are connected, each of said rollers being provided with a gear; of a main circuit; a circuit closer therefor; an electro-magnet included in said 5 circuit; an armature associated with said magnet; a shunt circuit; a motor, a contact and a pair of reversing magnets included in the shunt circuit; a gear on the motor shaft; a rocking armature associated 10 with the reversing magnets; a spindle carried by the second-named armature and provided with a pair of gears, one of which is constantly in mesh with the gear on the motor shaft, while the other gear is adapted 15 to mesh alternately with the gears on said rollers; a contact finger carried by the first-named armature for engagement with said contact when the first-named magnet is energized, to close said shunt circuit; and a 20 reversing switch for controlling said reversing magnets.

3. In an indicating apparatus, the combination, with a traveling indicating band, and winding rollers to which the band ends 25 are connected, each of said rollers being provided with a gear; of a rocking lever provided with a gear adapted to mesh alternately with the first-named gears; electro-magnetic means for operating said lever; 30 a motor; gear connections between said motor and the second-named gear; a shunt circuit wherein said motor and said lever-operating means are included; an electro-magnetically controlled device for 35 stopping said band; a main circuit wherein

said stopping device is included; a circuit closer for said main circuit; and means associated with said stopping device for closing said shunt circuit when said main circuit is closed.

4. In an indicating apparatus, the combination, with a traveling indicating band, and winding rollers to which the band ends are connected, each of said rollers being provided with a gear; of a rocking lever 40 provided with a gear adapted to mesh alternately with the first-named gears; electro-magnetic means for operating said lever; a motor; gear connections between said motor and the second-named gear; a shunt circuit wherein said motor and said lever-operating means are included; an electro-magnetically controlled device for stopping said band; a main circuit wherein said stopping device is included; a circuit closer for 45 said main circuit; means associated with said stopping device for closing said shunt circuit when said main circuit is closed; a signal; a signal circuit; and means associated with said stopping device for closing 50 said signal circuit when said main circuit is closed.

In testimony whereof, we have hereunto set our hands in presence of two subscribing witnesses.

ARTHUR JOHN WILLIAM MUNDEN.
JOHN MITCHELL MUIR.
